Specification for Design.

Patented Nov. 23, 1920.

Application filed December 9, 1919. Serial No. 343,614. Term of patent 3½ years.

To all whom it may concern:

Be it known that I, THEODORE D. MILLER, a citizen of the United States, residing at Verona, in the county of Essex and State of New Jersey, have invented a new, original, and ornamental Design for Hooks for Costumiers and the like, of which the following is a specification, reference being had to the accompanying drawing, forming part thereof.

Fig. 2 is a side elevation of the hook, and Fig. 3 is an edge view thereof.

I claim:

The ornamental design for a hook for costumiers and the like, as shown.

THEODORE D. MILLER.
